DESIGN FOR A FAVOR

Nell Roberts, Cuyahoga Falls, Ohio

Application September 18, 1940, Serial No. 95,183

Term of patent 14 years

To all whom it may concern:

Be it known that I, Nell Roberts, a citizen of the United States, residing at Cuyahoga Falls, in the county of Summit and State of Ohio, have invented a new, original, and ornamental Design for a Favor, of which the following is a specification, reference being had to the accompanying drawing, forming a part thereof.

What is claimed is:

The ornamental design for a favor, substantially as shown.

NELL ROBERTS.
